UNITED STATES PATENT OFFICE.

FRANK G. DUNBAR, OF CHICAGO, ILLINOIS, ASSIGNOR TO SARGENT COMPANY, OF CHICAGO, ILLINOIS, A CORPORATION OF ILLINOIS.

GAGE-GLASS HOLDER.

1,050,926.

Specification of Letters Patent. Patented Jan. 21, 1913.

Application filed February 19, 1912. Serial No. 678,448.

To all whom it may concern:

Be it known that I, FRANK G. DUNBAR, a citizen of the United States, residing at Chicago, in the county of Cook and State 5 of Illinois, have invented certain new and useful Improvements in Gage-Glass Holders, of which the following is a specification.

This invention relates in general to gage-glass holders and aims to produce a device 10 of this character, particularly adapted for employment in connection with gage glasses which are connected at one end with a gage cock and at their upper ends with the top of a boiler through a flexible connecting tube, 15 which will afford a simple and effective device for holding the tubular gage glass, to prevent vertical separation of the connections at the ends of the gage glass, and which will provide for the protection of the 20 gage glass without obstructing the view of the same and will prevent particles of broken glass from flying in the cab in case the gage-glass should burst or become otherwise accidentally broken while in use.

25 For the purpose of facilitating the explanation of my invention I have illustrated on the accompanying drawings one practical form thereof from a consideration of which, in connection with the following description, the invention in one of its preferred embodiments will be readily understood.

Referring to the drawings—Figure 1 is a front elevation of a gage glass holder embodying my invention; Fig. 2 is a longitudinal sectional view thereof; and Fig. 3 is a transverse sectional view taken on the line 3—3 of Fig. 1.

By reference to the drawings it will be 40 observed that a gage cock 5 of any well known or preferred construction is threaded into the end of a boiler 6 in the usual way. In certain types of gages a companion gage cock, similar to the cock 5 illustrated, is 45 also threaded into the boiler end some distance above the lower cock, but in the form of gage with which my invention is particularly adapted to be used the upper end of the gage glass is connected with the top

of the boiler through a flexible tube. This 50 manner of connecting the gage with the top of the boiler is believed by many to possess certain advantages in that dry steam from the top of the boiler is introduced into the gage-glass above the water level therein regardless of the height of the water in the 55 boiler. When a flexible tube is employed to connect the upper end of the gage-glass with the boiler, obviously some rigid form of support must be employed for holding 60 the gage-glass and preventing lateral movement of the upper end thereof which would result in breaking the glass. It is for the purpose of providing a rigid support for the gage-glass, to prevent breakage of the 65 same and also for the purpose of holding a gage-glass shield around the gage-glass, that my present invention was designed.

The gage-glass 7, of usual construction and any desired length, has its lower end 70 connected with the gage cock 5 in the usual manner. The holder, designated generally by reference character 8, is preferably made integral and for cheapness in manufacture 75 may be cast in one piece. This holder comprises a back provided with a longitudinally extending opening 9 through which light 80 may pass so that the water level in the gage-glass may be readily observed. The back is provided at its side edges with forwardly extending flanges 10 and 11, respectively, adapted to receive therebetween the rear edges of a horse-shoe-shaped shield 12. The ends of the holder are provided with 85 forwardly extending upper and lower flanges 13 and 14, respectively, between which the upper and lower ends of the shield 12 are adapted to be slid into position. The lower end of the holder is threaded as indicated at 15 for engagement with the gage 90 cock and the upper end is similarly threaded at 16 for engagement with a coupling 17 to which the flexible tube 18 connected at one end with the top of the boiler is attached by means of the packing nut 19. It will be 95 noted that the threaded sockets 15 and 16 are form tubular couplings carried by the respective ends of the holder.

The ends of the holder at the bases of the threaded sockets or tubular couplings 15 and 16 are provided with perforations to receive the gage-glass 7 and, when the parts are assembled as shown in Figs. 1 and 2, the holder affords a rigid support for the upper end of the gage-glass thereby preventing vibrations and lateral movements of the glass such as would fracture the glass were the tube 18 connected directly thereto and no holder provided for steadyng the glass. The shield 12, preferably made of wire glass, is slipped into position between the upper and lower flanges 13 and 14 so that its rear edges are embraced by the side flanges 10 and 11. The flanges 13 and 14 are provided with openings to receive a retaining and locking rod 20. This rod is preferably made of spring material and is curved as shown in Fig. 2 so that after it is inserted through the flanges 13 and 14 it may be given a quarter turn into the position shown in Fig. 2 to bring the bent portion into engagement with the shield 12 thereby forcing it tightly against the holder and locking it in place and preventing it from rattling. In order to hold the rod 20 in locked position the opening 21 in the flange 13 is preferably elongated, as shown in Fig. 3, to receive the lower portion of the loop 22 formed on the upper end of the rod 20 whereby said rod is prevented from turning. A small key 23 may be inserted through the lower end of the rod, if desired, to prevent the same from working out.

From the foregoing it will be manifest that I have provided a simple and substantial holder adapted to steady the upper end of the gage-glass and also to afford a support for a gage-glass shield. The flanges on the holder, together with the locking rod, retain the shield in position around the glass thereby protecting the engineer from flying fragments in case the gage-glass should become broken and the open back of the holder together with the glass shield permit the water level in the gage-glass to be readily observed. Furthermore, it will be obvious that while protecting the gage-glass and also affording protection to the engineer I have not obscured the gage-glass or placed any obstacles around the glass which would interfere with its observation. The invention, however, is, in its broad aspect, not limited to the details of construction illustrated and described, but obviously the structure may be varied within wide latitude without exceeding the scope of the invention.

60 I claim:

1. A gage glass holder comprising a back having top and bottom flanges projecting at the front of the back and rigidly fixed thereto, said flanges having alined openings for the reception of a tubular gage glass, the

front and sides of the holder being open to expose the tubular gage glass to view, and a tubular coupling provided upon each of the top and bottom flanges in alinement with the opening therein, substantially as described. 70

2. A gage glass holder comprising a back having top and bottom flanges projecting at the front of the back and rigidly fixed thereto, said flanges having alined openings for the reception of a tubular gage glass, the front and sides of the holder being open to expose the tubular gage glass to view, a tubular coupling provided upon each of the top and bottom flanges in alinement with the opening therein, and a gage glass protector carried by the holder and extending from one flange to the other flange, substantially as described. 75

3. A gage glass holder comprising a back having top and bottom flanges projecting at the front of the back and rigidly fixed thereto, said flanges having alined openings for the reception of a tubular gage glass, the front and sides of the holder being open to expose the tubular gage glass to view, a tubular coupling provided upon each of the top and bottom flanges in alinement with the opening therein, and a gage glass protector carried by the holder and extending from one flange to the other flange, each of the flanges having portions extending in front of the protector and provided with openings, and a locking rod extending through said openings and in contact with the protector to hold the same against lateral displacement. 90

4. A gage-glass protector comprising a holder adapted to accommodate a gage-glass and a gage glass shield said holder including a back provided on its longitudinal edges with flanges to accommodate therebetween the longitudinal edges of the gage-glass shield and provided at its top and bottom with flanges rigidly fixed to the back and adapted to accommodate therebetween the ends of said gage-glass shield. 105

5. In a gage-glass protector, the combination of a holder adapted for engagement at one end with a gage cock and at its other end with a flexible tube, said holder being provided with oppositely disposed flanges, a gage-glass shield positioned between said flanges, and yielding means for locking said shield in position. 115

6. In a gage-glass protector, the combination of a holder adapted for connection at its ends with a gage cock and a flexible tube, said holder being provided with side flanges and top and bottom flanges, a gage-glass shield positioned between said flanges, and a resilient bent rod engaging with said upper and lower flanges and adapted to yieldingly lock said shield in position. 125

7. In a gage glass holder and protector, 130

the combination of a holder comprising a back provided at its top and bottom with outstanding flanges fixed to the back, a gage glass shield disposed between said flanges, the space between the flanges being unobstructed at the front of the device to permit of the gage glass shield being laterally slid into and out of operative position, and means to detachably retain the shield upon the holder, substantially as described.

FRANK G. DUNBAR.
